Primary Examiner — Daniel J Domino*Assistant Examiner* — Samina Vieth(74) *Attorney, Agent, or Firm* — Birchwood IP(57) **CLAIM**

The ornamental design for a protective case for tablet, as shown and described.

DESCRIPTION

FIG. 1 is a front, right and top perspective view of a protective case for tablet, showing my new design;
 FIG. 2 is a rear, left and bottom perspective view thereof;
 FIG. 3 is a perspective view of the protective case for tablet thereof shown in an alternate configuration;
 FIG. 4 is a front view thereof;
 FIG. 5 is a rear view thereof;
 FIG. 6 is a left side view thereof;
 FIG. 7 is a right side view thereof;
 FIG. 8 is a top plan view thereof; and,
 FIG. 9 is a bottom plan view thereof.
 The broken lines shown in the drawings illustrate portions of the protective case for tablet that form no part of the claimed design.
